PNEUMATIC WASHING MACHINE
AND DRIERHarry Lamb, Seattle, Wash., assignor of one-half
to Clarence M. Ambrose, Seattle, Wash.

Application September 8, 1934, Serial No. 743,296

5 Claims. (Cl. 68—37)

My present invention relates to the washing machine art and more particularly to a pneumatic washing machine and drier.

Realizing the advantages of a machine in which a current of air, under considerable pressure, might be used in place of a mechanical agitator many attempts have been made to produce air operated machines. Considerable difficulty has been encountered in producing the degree of agitation necessary for thoroughly washing clothes without expending a large amount of energy to drive the air circulating means. Other difficulties encountered was the tendency for the clothes, particularly the large flat work, to become filled with air and to be carried up to the top of the machine and, in this way, not only ceasing to be agitated as is necessary for a thorough cleaning of the clothes but to further prevent the free circulation of the agitating air. In my present equipment I believe I have overcome these difficulties.

Instead of passing the air which is under pressure up through stationary openings in the bottom of the laundry tub, as is usual, I have provided a rotary air distributor operating on the general principles of a lawn sprinkler, for instance, so arranged that when the air is expelled from the distributor it causes the distributor to revolve on a horizontal plane at the bottom of the tub. This means that the air is at maximum volume and pressure at two points of the tub at any one instance, and the points of delivery are constantly changing so that a turbulence or agitation is accomplished that could not be accomplished by expenditure of the same amount of air being discharged through a plurality of fixed openings.

I have further arranged that the two arms of the air distributor are of unequal length so that one discharges its air in a circle near the center of the tub, while the other, which is diametrically opposite it, discharges its air on a larger diameter near the outer margin of the tub. This has a tendency to create a circulation of the clothes in the tub. The short discharge arm tends to force the clothing from the center out towards the outer edge of the tub, while the outer discharge nozzle tends to force the clothes from the periphery of the tub towards the center. Inasmuch as the two discharge openings are on opposite sides of the tub they cannot ever counteract each other, and further in this manner a thorough agitation of the clothes is accomplished. It further prevents the packing of the clothes in any one spot and the creating of a relatively free passageway for the air up through the water,

which is so often experienced with stationary air discharge openings. I have further provided that in case of flat work billowing up and being supported at the upper portion of the tub by the incoming air to the extent that it might seal the same and prevent a free flow of air, that it is arranged that this built up pressure will cause the water from the bottom of the tub to be forced upwardly and out on top of such clothes, sinking them down in the tub and permitting the operation of the washer as intended.

A further characteristic of my present design is that the same air is forced through the tub repeatedly, which means that the water in the tub is not being cooled off by the introduction of cold air.

Other and more specific objects will be apparent from the following description taken in connection with the accompanying drawings, wherein

Figure 1 is a vertical sectional view through a washer and drier made after the teachings of my invention.

Figure 2 is a sectional view taken along the line 2—2 of Figure 1.

Figure 3 is a sectional view taken along the line 3—3 of Figure 1.

Figure 4 shows in fragmentary elevation, the exterior of my washer and drier and the manner in which they are secured together in operating relationship.

Referring to the drawings, throughout which like reference characters indicate like parts, numeral 6 designates the main tank or tub of my washer. This is fitted with a lid 8 which is secured in tight engagement with the top of the tub as by a plurality of coacting lugs and latches 9. Cover 8 is provided with a cylindrical spacing or shield member 10 which is fixedly secured to the lid and flanged outwardly at 11 so as to closely engage the interior of tub 6. This arrangement provides an annular passageway 12 extending entirely around the inner surface of tub 6. Shield member 10 is provided, at its upper extent, with a plurality of openings 14 so that air passageway 12 is freely communicating with the interior of tub 6 providing that air may be drawn therefrom through the exhaust tube 16, yet any upward surge of water within the tub will not be drawn down tube 16 into the air propelling fan 18.

Secured to shield 10, at its lower extent, is a screen shield 19. The purpose of this shield is to prevent clothes, which might be forced upwardly by pocketing air, being carried up high

enough to interfere with the free circulation of air under impulse of fan 18.

Disposed at, or near, the center of tub 6 is the air inlet pipe 20, concentrically disposed about pipe 20 is a closed end tube 22 arranged with its closed end upwardly. This tube is fixedly secured to the bottom of tub 6 as by riveting the same at 24. Support tube 22 has, disposed concentrically about it, the central flow pipe 26. In the present showing this pipe is shown as supported from and secured to the lower screen 28, which screen in turn is supported by pipe 22 and also by the tub liner 39, it may be secured thereto but, for convenience in cleaning the tub, screen 28 should be removable with tube 26.

Revolvably disposed about tube 22 is the air distributor 31. The exact construction of this distributor is probably best illustrated in Figure 3 wherein a short arm 32 and a long arm 34 are provided. Each of these portions terminate in an air discharge opening as 35 and 36, respectively. These, following the general principles of rotary sprinklers, face in opposite directions and assist each other in causing the distributor to be revolved as air is projected under pressure from openings 35 and 36. Air is supplied to the distributor by means of a plurality of openings 38 in pipe 22. The course of the air under pressure from fan 18 is up tube 20 then down around tube 20, as inclosed by tube 22, and out openings 38 into distributor 31. The principal reason for this construction being to provide that water cannot back up through distributor 31 when the air blast is not turned on and thus find its way back into fan 18. Shield 30, used normally only in tubs of the larger sizes, is disposed concentric with tub 6 and provides an annular passageway from the bottom of the tub upwardly to the point where it discharges out over onto screen 19 for a purpose which will be more fully stated in the method of operation.

Feeling that no washing machine is complete without either a wringer or a drier, I have provided in combination with my washer a spinner type drier, the same being probably best illustrated in Figures 1 and 2. It consists essentially of a closed tub 40 which has centrally disposed therein the vertical shaft 41. On this shaft is suitably journaled as by bearings 42 and 43, the spinner proper 44. In the present illustration I have shown bearing 42 and 43 as being supported from a central tube 46 which is fixedly secured to tub 40. Spinner 44 is provided with a solid bottom and a centrally disposed central tube, which also is solid, as 48. This serves to adequately house bearings 42 and 43 and protect them from water particularly. The periphery of the spinner is formed by the perforated cylinder 50. Fixedly secured to cylinder 50 are a plurality of impeller blades 52 which are adapted to receive a blast of air from nozzle 54 and thus drive the spinner with a rapid, rotary movement. This action causes the drier to expel the moisture from the clothes after the well known principles of centrifugal driers. To confine the drying air within spinner chamber 40 I provide a cover 56 which is adapted to be firmly secured in close engagement with the upper surface of tub 40, and I further provide a cone shaped deflector 57 which tends to definitely confine the air, even though cover 56 be removed for a momentary inspection. An exhaust outlet for the spent air is provided at 58. As a matter of convenience and further to assist the drier in rapidly dissipating any water thrown out of the clothes, I

provide an annular channel shaped, removable screen container 60 composed of the lower screen 61 which is spaced well away from bottom 44, a central cylindrical screen 63 spaced well away from the central protecting tube 48 and the outer screen 64 which is spaced a like amount away from the perforated plate 50. It is to be understood that the three screens are actually formed as a unit so that it may be lifted out and carry with it the clothes that have been dried and thus avoid unnecessary handling of the garments.

Method of operation

In operating my device as a washer the tub is filled approximately half full of water, together with the necessary soap or other cleaning agent. The clothes to be washed are placed inside of the shield 30 and the cover 56 replaced. This holds the clothes in the space between screens 19 and 28. Fan 18 is then started, this may be driven by any suitable means, as an electric motor M. Air is then drawn downwardly through tube 16 out the pump discharge 66 past valve 67, which should then be in position shown in Figure 1, up tube 20, down the annular passageway between tubes 20 and 22, out opening 38 and then out through the discharge openings 35 and 36, formed within distributor 31. The air thus forced into the machine is distributed at two concentrated points and, due to the revolving of distributor 31, these two discharge points are continuously moving around the tub, under screen 28, so there is no interference from the clothes. The air, so introduced, should be under considerable pressure so that a rather violent bubbling action is obtained. It will be apparent it is believed that the shorter arm 32 will create, in effect, a discharge circle immediately adjacent to tube 26 whereas the outwardly disposed discharge opening 36 will create a circle for the discharge of air out adjacent to the periphery of the tub. This has a tendency to throw the clothes from the outside of the tub towards the inside and the shorter arm 32 tends to throw the clothes from the inside or central portion of the tub out towards the periphery. As the discharge openings are on opposite sides of the tub they do not interfere with each other and, in this way, produce a most vigorous agitation of the clothes which soon effects their cleansing.

One difficulty encountered in the past, which my present device overcomes, is the fact that the air blowing through the clothes, particularly flat work and the like, tends to billow it upwardly and thus interfere with the normal flow of the air upwardly through screen 19, out openings 14 and passageway 12 and then down tube 16. To overcome this possible contingency I have provided the annular passageway 70 which extends clear around the tub and the central passageway formed by tube 26. If the clothes do lodge against screen 19 to the extent that they interfere with the free flow of air therethrough, it immediately builds up a pressure within the washing chamber proper 72 which, acting upon the water which half fills the tube, is sufficient to force it up the central tube 26 and up the peripheral passageway 70 so that the water flows up over the top of screen 19. This flow of water quickly sinks any clothes that may be pressed up against screen 19 causing them to recirculate through the washer and provides for the continued effective washing of the clothes.

It will be particularly noted, it is believed, that fan 18 circulates the original air in the washer

at the time it is closed. As a result this air soon becomes warm and does not have any further tendency to cool off the water in the tub, as might be experienced if the air were drawn from the outside and expelled.

5 As soon as the clothes are washed they are removed from chamber 12 and placed in screen 60. Valve 67 is then revolved 90 degrees so that the air from discharge pipe 66 will be passed 10 out through conduit 74 to jet 54. The impinging of the air or propeller blades 52 soon create a high rotative speed in spinner 44. This acting under the principles known to centrifugal driers quickly expel sufficient of the water so that the 15 clothes may be ready for further processing, ironing and the like.

I have further provided that shaft 41, which revolves within tube 46, and is fixedly secured to the runner and revolves with it, is the driving 20 shaft for a water pump of the impeller type 16. This pump is adapted to draw water from the spinner tub 40 after the showing of the valve setting in Figure 1. If it is desired to draw water from tub 6 valve 78 must be revolved 90 degrees 25 so as to provide a clear passageway between washer discharge pipe 79 and the pump suction line 80. A discharge hose 81 is provided. This may be led to any convenient discharge or it may be used to put the water back into tub 6 30 if that is desired.

The foregoing description and the accompanying drawings are believed to clearly disclose a preferred embodiment of my invention but it will be understood that this disclosure is merely illustrative and that such changes in the invention 35 may be made as are fairly within the scope and spirit of the following claims.

Having thus fully described my invention what I claim as new and desire to secure by Letters 40 Patent is:

45 1. In a pneumatic washing machine, the combination with a water receptacle having inner and outer walls, a pair of spaced, horizontal screens mounted on the inner wall, and a rotary, motive-fluid-operated air distributing nozzle mounted below the lower screen, of an inner wall having perforations at its top portion, located above the upper screen and forming an air chamber, and means for withdrawing air from said chamber 50 and introducing the air to said distributor nozzle.

50 2. In a pneumatic washing machine, the combination with an enclosed tub having inner and

outer casings, upper and lower screens mounted on said inner casing, of a rotary, motive-fluid-operated air distributor mounted below said lower screen, an inner annular perforated wall above said upper screen spaced from the outer casing 5 and forming an air chamber, a fan and suction pipe for withdrawing air from said chamber and means for conveying the air under pressure from the fan to said distributor.

3. In a washing machine, the combination with 10 a closed tub having a pair of spaced screens forming upper and lower fluid chambers, a pneumatic distributor, a fan, and fluid conduit connections between said distributor, fan, and upper chamber, whereby air is withdrawn from said upper chamber 15 and ejected from said distributor, of a central tube connecting said chambers, an air pipe located within the tube and having an open upper end, and a closed return pipe also within the tube and surrounding the first mentioned air pipe, 20 for preventing water from flowing into the fan.

4. In a washing machine, the combination with 25 a closed tub formed with inner and outer casings and having a pair of spaced screens mounted on said inner casing forming upper and lower fluid chambers, a pneumatic distributor, a fan, and fluid conduit connections between said upper chamber, fan, and distributor, whereby air is withdrawn from said upper chamber and ejected 30 under pressure from said distributor, of a central tube connecting said chambers, an air pipe located within the tube and having an upper open end, and a return air tube closed at the top and opening into the air distributor also within the tube and surrounding said air pipe, for preventing 35 water from flowing into said fan.

5. In a washing machine, the combination with 40 a closed tub comprising inner and outer casings, the lower open end of said inner casing terminating above the bottom of the outer casing, a 45 pair of spaced screens mounted on said inner casing forming upper and lower fluid chambers, a pneumatic distributor, and means for withdrawing air from said upper chamber and ejecting the air from said distributor, of a central tube connecting said chambers, an air pipe located within the tube and having an open upper end, and a return air tube closed at the top and opening into the air distributor also within the central tube and surrounding said air pipe. 50

HARRY LAMB.
